UNITED STATES PATENT OFFICE.

JOHN RUSH GREEN, OF SOMERVILLE, MASSACHUSETTS.

SHOE-RACK.

1,278,332.

Specification of Letters Patent. Patented Sept. 10, 1918.

Application filed November 21, 1917. Serial No. 203,075.

To all whom it may concern:

Be it known that I, JOHN RUSH GREEN, a citizen of the United States, and resident of Somerville, county of Middlesex, State 5 of Massachusetts, have invented an Improvement in Shoe-Racks, of which the following description, in connection with the accompanying drawing, is a specification, like characters on the drawing represent- 10 ing like parts.

This invention relates to improvements in racks, standards or similar structures generally employed to support objects. In the form disclosed in the drawings, this invention is shown as applied to racks such as are used to support boots and shoes while in the factory and undergoing the various processes of manufacture. These racks are so constructed as to be readily movable from 15 one part of the factory to another and in such movement are subjected to hard usage.

Shoe racks of this type are almost constantly being pushed or pulled from place to place by the operatives. The most convenient gripping point is one of the uprights and hence these uprights tend to be distorted from their normal position with the result that the side and end or transverse members become loosened and tend to part 20 and the whole rack rapidly deteriorates. This invention discloses a rack so constructed that its parts are firmly held together and locked in position.

The object of this invention is to produce 35 a durable and efficient rack. A more specific object is to produce a rack in which the members forming the rack are held or substantially locked in normal position.

Other objects will more fully appear from 40 the following description and will be pointed out in the annexed claims.

In the accompanying drawing, there has been disclosed a structure designed to carry out the objects of the invention but it is to 45 be understood that the invention is not confined to the exact features shown, as various changes may be made within its reasonable scope.

In the drawings, 50 Figure 1 is a perspective of the rack; Fig. 2 is a section on the line 2—2 of Fig. 3; Fig. 3 is a section on the line 3—3 of Fig. 1; Fig. 4 is a detail view showing means of 55

attachment of an end member to an upright.

The rack frame in this selected embodiment consists of four uprights 1 which are preferably mounted in pairs on two base bars 60 2, an upright being secured adjacent each of the ends of the bars. Reinforcing rods 3 function to increase the strength and rigidity of this lower part of the rack while similar rods 4 reinforce adjacent pairs of 65 uprights. Spacing rods 5 are employed to hold the base bars 2 in definite spaced relation while casters 6 are provided at each end of the bars 2 in order that the rack may be readily moved from place to place in the 70 establishment by the operative. These uprights bear a plurality of side members 7 which are arranged in opposed pairs. Boots, shoes, etc., are supported, usually in inverted position, by pairs of adjacent rods 8. 75 Each pair of rods is preferably separated by means of a dividing bar 9 presenting separate rack compartments. In such position upon these racks, the articles are moved about the factory during the various steps 80 in their construction. When a shoe rack of this general type is pulled or pushed by an operative, an upright is usually grasped. Hence, the major strain comes upon the upright which eventually becomes distorted 85 from normal spaced relation to the other uprights and the ends of the side members 7 are loosened in their union with the uprights and rapid destruction of the shoe rack results. It is more particularly to the 90 means for securing the ends of these side members 7 to the uprights that this invention is directed. The side members 7 are provided at each end with terminal portions which are preferably countersunk in 95 opposed faces of the uprights while locking members are provided which are positioned between two adjacent uprights so that their ends abut against the countersunk portions of the side members. In this preferred embodiment of the invention, the terminal portions of the side members are shaped to form integral tongues 10, which are reduced on three sides from the surfaces of the side members. These tongues 10 are each countersunk in the uprights in such a manner 100 that the unreduced sides of adjacent tongues are opposed and preferably in the vertical plane of the surface of their respective uprights. These tongues 10 may be secured in 105

position by nails 11 driven through the tongue and into the upright.

The countersunk portions of the side members are each locked in position in the uprights by means of the reinforcing end transverse bars 12. These bars are alike and are made of a width substantially equal to the distance between two adjacent uprights. These transverse bars 12 are positioned so that their ends abut against opposed faces of adjacent tongues 10. In order that each of these transverse bars 12 may be easily applied and retained in locking position, each end of the bar is provided with an eccentric terminal projection adapted to be received in holes in the upright. Such projections are preferably tenons 13 provided near one side of each end face of each bar 12. These tenons may be inserted in their holes before the tongues 10 of the side bars are positioned as each bar 12 may be turned about its tenons as pivots into a position out of the way for the emplacement of the countersunk tongues. Such position is shown at the right in Fig. 2. After the countersunk tongues are positioned in the uprights and nailed, the transverse bars 12 are upwardly turned into the reinforcing and the locking position shown on the left in Fig. 2. A fastening means such as a nail 14 may be driven through each tenon into the upright and thus to hold the transverse bars against rotation.

There is thus provided an efficient and durable frame structure which is particularly adapted for use in movable boot and shoe racks.

Having thus described my invention, what I claim as new and desire to secure by Letters Patent, is:

1. In a rack the combination of uprights, side members, the side members having terminal portions countersunk in opposed faces of adjacent uprights, and transverse members, the terminal faces of each transverse member abutting against opposed faces of the countersunk portions of two adjacent side members.

2. In a rack the combination of uprights, side members, a terminal tongue at each end

of each side member, the said tongues being countersunk in opposed faces of adjacent uprights, and transverse members secured to the uprights with the terminal faces of each transverse member respectively abutting against opposed faces of the countersunk terminal tongues of two adjacent side members.

3. In a rack the combination of uprights, side members, the side members having terminal portions countersunk in opposed faces of adjacent uprights, and transverse members, the transverse members having terminal projections securing the members to the uprights with the terminal faces of each transverse member respectively abutting against opposed faces of the countersunk portions of two adjacent side members.

4. In a rack the combination of uprights, side members having terminal portions countersunk in opposed sides of two adjacent uprights, transverse members, and eccentric terminal projections on each end of said transverse members, mounted in holes in the uprights, the oppositely extending projections of each transverse member being received in said opposed sides adjacent said countersunk portions whereby, after emplacement of said countersunk portions, each transverse member may be eccentrically turned about its projections to lock said countersunk portions.

5. In a rack the combination of uprights, side members having terminal portions countersunk in opposed sides of two adjacent uprights, transverse members, terminal projections on each end of said transverse members, the oppositely extending projections of each transverse member being mounted in holes in said opposed sides adjacent said countersunk portions, whereby, after emplacement of said countersunk portions, each transverse member may be turned about its projections to lock said countersunk portions, and means to prevent turning of said transverse members when in locking position.

In testimony whereof I have signed my name to this specification.

JOHN RUSH GREEN.
